DISPENSER FOR ROLLED PAPER

James L. Miller, Lake Worth, Fla.

Application May 9, 1952, Serial No. 286,928

2 Claims. (Cl. 242—55.5)

This invention relates to a novel dispenser of extremely simple construction primarily adapted for supporting and dispensing rolled paper towels and which is likewise well adapted as a holder and dispenser for rolled toilet paper.

More particularly, it is an aim of the present invention to provide a dispenser which may be very economically manufactured and sold for supporting a roll of paper from which any desired amount of paper may be unrolled and separated from the roll, thereby reducing waste in the use of paper removed from the roll.

Another and particularly important object of the present invention is to provide a rolled paper dispenser especially adapted for use in public places, having means to effectively prevent unauthorized removal and theft of rolls of paper towels and toilet paper and which is so constructed that it is substantially impossible to remove the roll of paper from the dispenser until all of the paper has been used.

Still another object of the invention is to provide a rolled paper holder and dispenser of one-part construction enabling the dispenser to be very economically manufactured and sold.

Various other objects and advantages of the invention will hereinafter become more fully apparent from the following description of the drawing, illustrating a preferred embodiment thereof, and wherein:

Figure 1 is an end elevational view showing the dispenser in an operative position;

Figure 2 is a front elevational view thereof;

Figure 3 is an enlarged vertical sectional view taken substantially along a plane as indicated by the line 3—3 of Figure 2;

Figure 4 is a fragmentary longitudinal sectional view taken substantially along a plane as indicated by the line 4—4 of Figure 3, and

Figure 5 is a fragmentary horizontal sectional view on an enlarged scale taken substantially along a plane as indicated by the line 5—5 of Figure 1.

Referring more specifically to the drawing, the rolled paper holder and dispenser in its entirety and comprising the invention is designated generally 6 and includes a substantially flat rear wall 7, a transversely rounded top wall 8 of a length which is coextensive with the length of the rear wall 7, having one longitudinal edge merging integrally with the upper edge of the rear wall 7, and a transversely rounded front wall 9 forming a continuation of the curvature of the forward part of the top wall 8 and which is likewise coextensive in length with the rear wall 7 and top wall 8. The bottom edge of the front wall 9 terminates substantially above the level of the bottom edge of the rear wall 7 and is notched to provide a toothed cutting edge 10, for a purpose which will hereinafter be described. The dispenser 6 also includes corresponding substantially parallel end walls 11 which are formed integral with the rear wall 7, top wall 8 and front wall 9. As best seen in Figure 3, the end walls 11 are provided with substantially straight bottom

2

edge portions 12 which are disposed in substantially the same plane as the bottom edge of the rear wall 7 and which merge therewith. Said end walls 11 are provided with upwardly curved bottom edge portions 13 which extend from the ends of the bottom edge portions 12, disposed remote to the rear wall 7, and which merge at their upper ends with the ends of the front wall 9. The bottom edge portions 12 and 13 of the end walls 11 combine with the bottom edge of the rear wall 7 and the toothed bottom edge 10 of the front wall 9 to define the open bottom 14 of the dispenser 6. The parts 7 to 11, inclusive, of the dispenser 6 are all integrally formed, as clearly illustrated in Figures 3, 4 and 5, so that the dispenser 6 constitutes a one-part construction capable of being readily stamped or molded.

The end walls 11 are provided with corresponding slots 15 forming integral tongues 16 which are spring biased inwardly of said end walls by the resiliency of the material of which the dispenser 6 is formed. Said tongues 16 which constitute integral parts of the end walls 11 are provided on their inner sides and adjacent their free ends with inwardly projecting substantially circular bearing elements 17, constituting integral parts of said tongues 16. Said inwardly extending projections or bearing elements 17 are provided with inclined inner faces 18 which slope downwardly and outwardly away from one another and toward the adjacent end walls 11. As seen in Figure 4, the bottom edge 18 of each face 18 is spaced from the inner surface of the tongue 16, individual thereto.

The rear wall 7 is provided with longitudinally spaced openings 19 to receive driven fastenings 20 which extend outwardly therethrough and are embedded in a wall or upright member 21 for securing the dispenser 6 to the wall 21 and so that its open bottom 14 will open downwardly. The fastenings 20 preferably constitute wood screws and the front wall 9 is preferably provided with openings 22, disposed in alignment with the openings 19, through which a screwdriver or similar tool, not shown, may be inserted for driving the fastenings 20 into the wall or member 21.

Assuming that the dispenser is in an applied position, as illustrated in the drawing, a rolled paper towel of a conventional type, designated generally 23, comprising a tube 24 formed of cardboard or the like on which the paper towelling 25 is wound is adapted to be mounted in the dispenser. The dispenser 6 may obviously be made in various lengths to fit paper rolls 23 of different lengths and which may constitute rolls of paper towelling or other types of paper rolls, including toilet paper. The rolled paper 23 is inserted upwardly through the open bottom 14 of the dispenser 6. The ends of the uppermost portions of the rolled paper 23 will strike the inclined surfaces 18 of the bearing elements 17, which surfaces will function as cams to cause the resilient tongues 16 to be displaced outwardly and tensioned by the upward displacement of the paper roll 23. The tongues 16 can yield outwardly through the end wall openings 26 formed by said tongues and by the slots 15. When the roll of paper 23 has assumed a position so that the tube 24 is in alignment with the bearing elements 17, the tongues 16 will be spring biased by their resiliency inwardly, thereby causing the bearing elements to be projected into the ends of the tube 24 to thus rotatably mount the roll of paper 23 on said bearing elements and within the dispenser 6. All portions of the edges of the cam faces 18 will extend into the tube ends, so that said bottom edges 18 will be shielded by the tube ends to prevent an instrument being inserted between a cam face 18 and an end of the tube 24 for displacing the bearing element 17 thereof outwardly to a position out of engagement with the tube 24. Thus, removal of the roll of paper 23 from the holder will be prevented. The inner

sides of the outer, free ends of the tongues 16 will bear against portions of the ends of the tube 24 and portions of the ends of the rolled paper 25, as illustrated in Figure 5, to frictionally resist rotation of the paper roll 23 and so that only a desired amount of paper will be un-rolled at any one time from the roll of paper and only while the free end of the roll of paper, designated 27, is actually being pulled downwardly, thus avoiding unnecessary waste of paper. The free end 27 of the paper extends downwardly from the outermost portion of the paper roll 25 which is located near the front wall 9 and accordingly extends downwardly through the opening 14 adjacent the toothed cutting edge 10. It will thus be readily apparent that the end 27 may be pulled down to any desired extent and thereafter by lifting upwardly on one side edge of the extended end 27, said end 27 may be cut off by the toothed cutting edge 10. The free ends of the tongues 16 frictionally engage the ends of the roll of paper 23 with sufficient force to prevent un-rolling of the paper 25 during this cutting operation.

In initially applying the roll of paper 23 one end of the roller may be disposed above the level of the other end to engage the surface 18 of one bearing element 17 for displacing said bearing element outwardly and so that the opposite end of the roll of paper may then engage the surface 18 of the other bearing element to enable the roll to be inserted upwardly between the bearing elements for causing said bearing elements to be sprung outwardly and tensioned, as previously described. It will be readily apparent that it will be substantially impossible to remove the roll of paper 23 from the dispenser 6 when in a fully applied position, as illustrated in Figures 3, 4 and 5 since insufficient clearance exists between the edges of the tongues 16 and the wall portions defining the openings 26 to enable said tongues to be drawn outwardly of the walls 11. Thus, the possibility of rolls of paper towelling or rolls of toilet paper being stolen from public restrooms is thus reduced to a minimum. After the rolled paper 25 has been completely used, the cardboard tube 24 can be collapsed by a squeezing action and the ends thereof drawn together and thus disengaged from the bearing elements 17 so that a fresh roll of paper 23 can then be applied to the dispenser 6, as previously described.

The dispenser 6 may be formed of various materials such as various metals or plastics and may be stamped or molded. Due to the integral construction of all parts of the dispenser 6, it will be readily apparent that it can be very economically manufactured and will be very durable and efficient for accomplishing its intended result. The tongues 16 can be produced as a part of the stamping or molding operation and will possess sufficient resiliency to effectively support a paper roll and to effectively function as a brake to restrict the rotation of the roll in unwinding the paper therefrom. Likewise,

it will be readily apparent that the dispenser 6 may be made in various lengths and various cross sectional sizes to fit rolls of paper of different lengths and diameters.

Various modifications and changes are contemplated and may obviously be resorted to, without departing from the spirit or scope of the invention as hereinafter defined by the appended claims.

I claim as my invention:

1. A dispenser for rolled paper comprising an elongated housing having an open bottom through which a roll of paper is inserted into the housing, said housing including flat end walls having corresponding slots forming integral spring tongues, said tongues extending inwardly of the housing at a slight angle to the plane of the end walls and being resiliently disposed relatively to said end walls and capable of being sprung outwardly of the end walls through the openings therein formed by the tongues, each of said tongues having a projection on its inner side forming a bearing element, said projections 10 engaging in the ends of the bore of the roll of paper for rotatably supporting the roll of paper in the housing whereby the paper may be unwound from the roll and dispensed therefrom through the open bottom of the housing, said projections having corresponding inner 15 end surfaces inclined downwardly and outwardly relatively to one another toward the open bottom of the housing and forming cam surfaces engaged by the ends of the roll of paper when the roll of paper is inserted upwardly into the housing for displacing the spring tongues outwardly 20 of the housing through the end wall openings, all portions of the continuous edges of the inner ends of said projections, constituting the marginal edges of said cam surfaces, being spaced from the inner sides of the tongues, and said tongues being spring biased inwardly by the 25 resiliency thereof for causing all portions of the edges of the inner ends of said projections to enter the ends of the bore of the roll of paper when the projections are disposed in alignment with the bore for rotatably supporting the roll of paper and to prevent removal of the roll 30 of paper from the projections except by collapsing the core of the paper roll after the paper has been dispensed.

2. A dispenser as in claim 1, said projections being spaced from the free ends of said tongues, and said free ends of the tongues being spring biased into frictional 45 engagement against portions of the ends of the roll of paper to prevent free rotation and unwinding of the wound paper from said projections.
